F. G. Fisher,
ATTORNEY.

UNITED STATES PATENT OFFICE.

IVAN S. PERKINS, OF GUYMON, OKLAHOMA.

INDICATOR.

1,308,914.

Specification of Letters Patent. Patented July 8, 1919.

Application filed January 28, 1918. Serial No. 214,049.

To all whom it may concern:

Be it known that I, IVAN S. PERKINS, a citizen of the United States, residing at Guymon, in the county of Texas and State 5 of Oklahoma, have invented certain new and useful Improvements in Indicators, of which the following is a specification.

My invention relates to improvements in indicators, and my object is to provide a 10 device which can be employed to advantage by bankers, real estate and other office men to advise their clients of legal holidays, when they will return if called out, and all other information they may wish to impart 15 through a medium of this character.

The device is adapted to be placed on office doors, desks and other prominent places, and it embodies a ribbon bearing all necessary notices and other information, and 20 adapted to be adjusted to bring the desired notice or message into plain view of all interested parties.

Referring to the accompanying drawing, which shows one particular embodiment of 25 the invention:

Figure 1 is a perspective view of the device.

Fig. 2 is a vertical, transverse section, on line II—II of Fig. 1.

30 Fig. 3 is a vertical section taken on line III—III of Fig. 2.

Fig. 4 is a fragmentary elevation of one end of the message bearing ribbon, and Fig. 5 is a perspective view of a key.

35 In carrying out the invention, I employ a cabinet 1, having a door 2 operably-connected thereto by hinges 3, so that access may be readily had to the message bearing ribbon 5 and the mechanism within the cabinet.

40 As disclosed by Fig. 1, the door 2 closes the front and top of the cabinet and thus excludes therefrom rain, snow, etc., when the cabinet is placed on the outside of a building.

45 Preferably, the cabinet 1 and the door 2 are made of sheet metal, although other materials may be used, and the door 2 is provided with a window 6 through which the message and notices printed or written

50 upon the ribbon 5 can be observed. Said door 2 is also provided with a lock 7 to prevent unauthorized persons from gaining access to the interior of the cabinet and tampering with the mechanism arranged 55 therein.

The forward portions of the side walls 9

of the cabinet are, prevented from springing toward or away from each other by a pair of transverse stay members 10, removably-mounted upon studs 12, projecting from the 60 forward edges of said side walls 9, which are recessed as indicated at 13 to receive the ends of the stay members 10. The stay members 10 also retain the ribbon close to 65 the window 6.

15 designates a pair of spools removably-mounted within the cabinet to carry the ribbon 5. Each spool 15 is mounted upon a shaft 16, preferably, rectangular in cross section to cause the spool, which is removably-mounted thereon to rotate therewith for the purpose of adjusting the ribbon 5 to bring the desired notice or message opposite the window 6. Each shaft 16 has cylindrical journals 18 and 19 mounted in the side walls 75 9 of the cabinet 1, said side walls being provided with bearings 21 which provide comparatively broad surfaces for the journals 18 and 19. A stem 22 projects from the journal 19 of each shaft to receive the barrel 80 of a small key 25 whereby either shaft may be rotated, so that it may in turn rotate its respective spool to wind the ribbon 5 thereon.

Each stem 22 has a lateral projection 27 85 over which the slotted portion 28 of the key barrel 26 engages, so that when said key is rotated it will rotate the shaft therewith. The slot 28 has a rightangular extension 29 to receive the projection 27 on either shaft 90 16 when it is desired to withdraw the same from its respective spool and bearings in the sides 9 of the cabinet 1. In order to protect the stems 22 from damage they are arranged in recesses 30, formed in the adjacent side 95 of cabinet 1, said recesses being large enough to receive the barrel 26 of the key 25.

Each spool 15 has a pair of studs 32 projecting therefrom to removably-secure the ends of the ribbon 5 thereto, said ends having 100 perforations 33 to receive the studs 32.

40 designates a timepiece which in conjunction with certain instructions on the ribbon 5, indicates when the proprietor will return to his office. Said timepiece is mounted 105 in a lower corner of the door 2, which has an opening 41, so that the dial 42 and the hands 43 of the timepiece may be observed. The dial and the hands are, preferably, covered by a crystal 45, so that access 110 cannot be had to said hands by unauthorized persons for the purpose of rotating the

same, this operation being manually performed with a key 25, which is adapted to fit over a stem 46 geared in any suitable manner to the hands 43, for the purpose of actuating the same. The stem 46, has a lug 49 for engagement with the slotted portion 28 of the key 15.

When it is desired to bring any particular message on the ribbon into position before the window 6, the barrel of the key 25 is slipped upon the stem 22 of the proper shaft, with the slotted portion 28 engaging over the projection 27, after which said shaft may be rotated until the desired subject-matter is brought into position.

When it is desired to remove one ribbon and substitute another therefor, containing different subject-matter, the key 25 is slipped over the stem of each shaft until the angular extension 29 engages over the projection 27. The operator then pulls outwardly on the key, which operation withdraws the shaft, thus allowing the spool to be removed from the cabinet 1 and the ribbon to be removed, after which another ribbon is substituted, and the spools replaced in the cabinet.

From the foregoing description, it will be

understood that I have provided a device well adapted for the purpose intended, and while I have shown and described the preferred form of my invention, I reserve the right to make such changes in the construction, proportion, and arrangement of parts as properly fall within the spirit and scope of the appended claim.

Having thus described my invention, what I claim and desire to secure by Letters Patent, is:

In a device of the character described, a cabinet having a window therein, spools in the upper and lower portions of said cabinet, a ribbon connected to said spools and bearing information for exposure at the window, a timepiece mounted in the cabinet adjacent to the window for use in conjunction with information on the window, and winding shafts to the spools and said timepiece adapted to receive an operating key common to all of said shafts.

In testimony whereof I affix my signature in the presence of two witnesses.

IVAN S. PERKINS.

Witnesses:
